(57) **CLAIM**

The ornamental design for a protective gear, as shown and described.

DESCRIPTION

FIG. 1 is a front-side view of a protective gear showing our new design.

FIG. 2 is a rear-side view thereof.

FIG. 3 is a front perspective view thereof; and,

FIG. 4 is a rear perspective view thereof.

The broken lines in the figures depicting stitching are for environmental purposes only and form no part of the claimed design.
